DESIGN FOR A TYPEWRITER

William A. Dobson, Wethersfield, Conn., assignor
to Underwood Elliott Fisher Company, New
York, N. Y., a corporation of Delaware

Application March 21, 1936, Serial No. 61,718

Term of patent 14 years

To all whom it may concern:

Be it known that I, William A. Dobson, a citizen of the United States, residing in Wethersfield, in the county of Hartford and State of Connecticut, have invented a new, original, and ornamental Design for a Typewriter, of which the following is a specification, reference being had to the accompanying drawings, forming part thereof.

Figure 1 is a perspective view of a typewriter, showing the new design, the view showing the

machine when viewed from the front thereof.

Figure 2 is a perspective view of the typewriter of Figure 1, as viewed from the rear.

A conventional keyboard is used, and the dotted keys are merely shown for the purpose of illustration.

I claim:

The ornamental design for a typewriter, as shown and described.

WILLIAM A. DOBSON.
